Primary Examiner — Michael C Stout*Assistant Examiner* — Fitzgerald L Butac(74) *Attorney, Agent, or Firm* — Harvey Law, PC;
Derrick Harvey**CLAIM**

I claim the ornamental design for a dual entry bushing, as shown and described.

DESCRIPTION

FIG. 1 is a top perspective view of a dual entry bushing;
 FIG. 2 is a first side view thereof;
 FIG. 3 is a second side view thereof;
 FIG. 4 is a third side view thereof;
 FIG. 5 is a fourth side view thereof; and,
 FIG. 6 is a top view thereof.

The broken lines show portions of a dual entry bushing that form no part of the claimed design.
 The “dash-dot” broken lines are for the purpose of showing the bounds of the claimed design, and form no part thereof.
